UNITED STATES PATENT OFFICE.

JOHN Y. DAVIS, OF UNION SPRINGS, NEW YORK.

AUTOMATIC CAR-BRAKE.

SPECIFICATION forming part of Letters Patent No. 367,791, dated August 9, 1887.

Application filed February 26, 1885. Serial No. 157,096. (No model.)

To all whom it may concern:

Be it known that I, JOHN Y. DAVIS, a citizen of the United States, residing at Union Springs, in the county of Cayuga and State of New York, have invented a new and useful Automatic Car-Brake, of which the following is a specification.

My invention relates to improvements in automatic brake devices known as "automatic momentum brakes;" and the objects of my improvements are to cause the application or release of the brakes of a railway-car automatically by means of the momentum of the car or its resistance to the force applied at either draw-head. I attain these objects by the mechanism illustrated in the accompanying drawings, in which—

Figure 1 is a side view of a railway-truck with the device applied. Fig. 2 is an end view of same. Fig. 3 is a vertical section of the device on the line $x-y$ of Fig. 4. Fig. 4 is a top or plan view; and Fig. 5 is a view of a modification in the manner of connecting the draw-heads together.

Similar letters refer to similar parts throughout the several views.

A A represent the two draw-heads attached to the two extremities of the car. These draw-heads are connected in such a manner by means of a rigid draw-bar or its equivalent, as shown at B B, as to cause the horizontal movement of one draw-head to produce a like horizontal movement in the other, or pulling one will be the same as pushing the other, or pushing one will be the same as pulling the other. This object may be attained in various ways, one of which is shown in Fig. 1 and another in Fig. 5, which will be described hereinafter.

S S are the brake shoes, attached to the two extremities of the horizontal brake-beams K, to the center of the length of which are attached the vertical brake-levers F, connected at their lower extremities by the horizontal connecting-bar H, and provided at their upper extremities with the anti-friction rollers E E. The brake-shoes are swung from the frame of the car or truck by means of the links L, and are also allowed a vertical movement by having the upper ends of the links connected with the frame of the car or truck by means of a longitudinal loop or slot, as shown at N, Figs.

1 and 2, or having the lower ends of the links connected to the shoes in the same way.

C C are two projections attached to the upper side of the rigid draw-bar B in such a position that they will come into contact with and push the rollers E E whenever, by the movement of the draw-heads A A and their connecting-bar H, they are given that direction, providing the rollers are made to take the position in front of the projections by the vertical movements of the shoes S S, to which they are connected by means of the levers F and brake-beams K.

D D are stationary stops with which the rollers E will come into contact whenever the opposite roller is moved forward by the projection C.

In Fig. 5, A A are the opposite draw-heads, attached at their inner ends to the center of equalizing-levers X X, which are pivoted to the frame of the car at Y and connected at their extremities by the connecting-rods H.

It will be seen that this device connects the two draw-heads so as to give them a simultaneous movement in the same direction, the same as though they were attached to the extremities of the rigid draw-bar.

The operation of the device may be described as follows: Whenever any force is applied to push the rear draw-head or to pull the front one the car will take the same direction and cause the shoes and connections to take the corresponding direction whenever the shoes are in contact with the wheels, unless stopped by the links L coming into contact with one end of the loops at their ends.

As will be seen, the arrangement is such that the rollers E are carried from in front of the projections C whenever the projections C are thrust forward in the same direction as that in which the car is moving, and so releases the brakes, and that they will be kept in front of the projections whenever they are thrust in the opposite direction from that in which the car is moving, and so apply the brakes by the vertical movement of the brake-shoes to which the rollers E are connected, this vertical movement being given the shoes by their coming into contact with the rims of the wheels, against which they are pushed by the pressure of the projections C against the rollers E.

Whenever either of the rollers E is pushed forward by the action of the projections C, the shoes S, with which they are connected, are pushed against the rims of their wheels, and 5 serving as a fulcrum cause the lower end of the lever F to push the opposite shoes against their wheels, the roller at the top of the opposite lever coming into contact with the stationary stop D.

10 It being plain that the act of pushing against the front draw-bar or pulling the rear one being the same in this device, the resistance to the momentum of the moving car causes the draw-heads to move in the opposite direction 15 to that of the car, and by the operation of this device applies the brakes; also, pressing against the rear draw-bar being the same as pulling the front one, the resistance of the car to any force applied to either draw-head causes them 20 to move in the same direction as that of the car and by the operation of this device releases the brakes. Therefore any external force used 25 to resist the momentum of the car applies the brakes, and any external force applied to overcome the resistance of the car will release the 30 brakes, providing that external force is applied through the draw-heads; but if, after the car is stopped with the brakes set, it is desired to start it again in the opposite direction the 35 draw-head which was the front one will become the rear one and the external force applied will be an active force instead of a passive one, and the position of the several parts must adjust themselves to meet the opposite 40 conditions. This is effected by the reversal of the direction in which the wheels turn, reversing the position of the brake-shoes, and through their connections the relative positions of the rollers E and projections C.

45 The reversal of the direction of the wheels cannot be effected without being released from the brakes, and the brakes cannot be released until motion is imparted to the car which moves the wheels, so that the moving of the brake-shoes in the same direction as the rims of the 50 wheels will either cause their release or allow

of their release; or a complete automatic momentum brake must meet both requirements, that of applying an external force in such a manner as to cause the momentum of the car 55 to apply the brakes and the resistance of the same to release the brakes and also to cause the several parts to adjust themselves to a reversal of the direction in which the car had been moving. The first of these requirements, 60 as has been shown, is met by connecting the draw-heads A in such a manner that they will both move in the same direction when any force is applied to either; and the second requirement is met by so attaching the shoes to 65 the frame of the car or truck as that they may be moved in the same direction as the rims of the wheels with which they are in contact when the brakes are set, and by their connections to cause the relations of the parts to 70 change, or to allow of their being changed by the reversal of the direction of the wheels.

Having described my invention, what I claim, and desire to secure by Letters Patent, 75 is—

1. The combination of the car, the draw-heads having fixed connections with each other, and the brake-shoes connected to the draw-heads and to the frame and susceptible of moving with the rims of the wheels, substantially as described, whereby any force applied to either draw-head to resist the momentum of the car will apply the brakes and any force applied to either draw-head to overcome the 80 resistance of the car will release the same, as set forth.

2. The draw-bars having the projections C, in combination with the levers F, actuated by the brake-shoes, links L, and brake-beam K, substantially as described.

3. The combination of the levers F, bar H, draw-bar, stationary stops D, and projections C, substantially as described.

JOHN Y. DAVIS.
